UNITED STATES PATENT OFFICE.

WILLIAM HERBERT SUTTON, OF GLASGOW, SCOTLAND, ASSIGNOR TO J. & P. COATS, LIMITED, OF GLASGOW, SCOTLAND, A COMPANY OF GREAT BRITAIN AND IRELAND.

CHEESE-WINDING SPINDLE.

Application filed June 4, 1923. Serial No. 643,232.

To all whom it may concern:

Be it known that I, WILLIAM HERBERT SUTTON, a subject of the King of the United Kingdom of Great Britain and Ireland, and 5 residing at Glasgow, Scotland, have invented a certain new and useful Improvement in Cheese-Winding Spindles, of which the following is a specification.

This invention is concerned with the application of a removable segmental metallic clearance sleeve to a spring centre on which thread is cross-wound to form a cheese, the function of such sleeve being to separate the inner and outer protective stockings during 10 winding, so that on withdrawal of the sleeve after winding the pressure on the inner core of the cheese is reduced, that is, there is produced a cheese for dyeing purposes which is softer wound on the inside than the out- 15 side.

In the accompanying drawings which illustrate the invention Fig. 1 is a part axial section of the assembled device. Fig. 2 is a detail view of the clearance sleeve. Figs. 20 25 3 and 4 are views corresponding to Fig. 2 showing modifications.

Referring to the drawings, 1 denotes a segmental clearance sleeve adapted to be removably applied to a spring centre on which 30 thread is cross-wound to form a cheese, the function of such sleeve 1 being to separate the inner and outer protective stockings during winding, so that on withdrawal of the sleeve 1 after winding the pressure on the 35 inner core of the cheese is reduced.

2 denotes a metallic expanding sleeve secured in position on the spindle 3 by a nut 4 on the outer end.

A helical spring 5 is slipped over the expanding sleeve 2 and a knitted stocking 6 is then drawn over the spring 5 with ends of equal length projecting beyond the spring.

Two spring rings 7 are now passed over the stocking 6 to a position near the middle 45 thereof, the function of the spring rings 7 being to facilitate the assembly of the clearance sleeve on top of the stocking 6.

The clearance sleeve 1 as shown in Fig. 2 consists of a number of metallic plates or 50 segments 1^a shaped to form a cylinder of the required outside diameter of stocking. Each segment tapers from a broad end to a narrow end.

A slot 8 is cut in the broad end of each segment to facilitate withdrawal. 55

The segments are slipped underneath the spring rings 7 until the sleeve is complete; then the spring rings are moved one to each end of the sleeve.

Alternatively, as shown in Fig. 3 the clearance sleeve may consist of a number of plates or segments 1^b of which the broad end of each is soldered to an end ring 1^c which consolidates the sleeve into two parts, i. e., two rings having alternate clearance plates soldered thereon. 60

The clearance sleeve being in position covering the spring centre encased by the inner stocking 6, the outer knitted stocking 9 is now drawn over the top of the clearance 70 sleeve and rings (if used). The mounting of the spindle for winding purposes is thus completed.

The cheese is now wound and then removed from the spindle. 75

By means of a hook the clearance sleeve is now extracted, segment by segment, or, if the form of clearance sleeve shown in Fig. 3 be used, the rings with soldered segments are withdrawn and the cheese is now ready 80 for dyeing.

In the further modification shown in Fig. 4 the clearance sleeve composed of a number of plates 1^d, is soldered to end flanges 1^e mounted on a steel centre 1^f, the ends of which are rotatable in a suitable holder. A spring centre covered with a protective stocking is passed into part of the clearance sleeve before assembly of the latter; the clearance sleeve is then assembled, the outer stocking is drawn over the outside of the assembled clearance sleeve, and the cheese is wound on top, as before. To remove the cheese, one flange 1^e, on which two or three alternate plates are soldered, is withdrawn by means 90 of a key, and then the other flange, which is fixed to the steel centre and carries the remaining plates is drawn out. The cheese is now resting on the spring centre with two protective stockings between its inner core 100 and the spring. 95

What I claim is:

1. In combination with a spindle, a helical spring surrounding said spindle, a stocking surrounding said spring, a removable clearance sleeve comprising metallic segments 105

shaped to form a cylinder surrounding said stocking, and an outer stocking surrounding said sleeve.

2. In combination with a spindle, an expanding sleeve secured to said spindle, a spring surrounding said sleeve, inner and outer stockings surrounding said spring and a removable clearance sleeve interposed between said stockings, said clearance sleeve comprising tapered metallic segments re-

movable endwise in opposite directions, said segments shaped to form a cylinder when assembled.

In testimony whereof I have signed my name to this specification in the presence of ¹⁵ two subscribing witnesses.

WILLIAM HERBERT SUTTON.
